SCARFING MACHINE

Joseph M. Tyrner, Mendham Township, Morris County, N. J., assignor to Air Reduction Company, Incorporated, a corporation of New York

Application August 3, 1949, Serial No. 108,336

2 Claims. (Cl. 266-23)

1

This invention relates to scarfing machines for thermochemically scarfing or desurfacing billets, blooms, and similar metal bodies, and particularly to that type of scarfing machine which is adapted to scarf all four surfaces of a rectangular billet simultaneously.

Not only is it advantageous for a scarfing machine to be capable of scarfing the four surfaces of a rectangular billet simultaneously in a single pass, but it is also advantageous that the machine be able to accommodate billets of various sizes and not be restricted in use to any one size. Often in the course of a day's production a single conveyor roll of a steel mill will pass successive blooms or billets differing in size within a matter of a few minutes. Consequently it is desirable that the scarfing machine be extremely flexible in its accommodation of billets of different sizes and that it be possible to make the necessary changeover adjustments rapidly.

Scarfing machines have already been built that will scarf all four surfaces of a rectangular billet simultaneously. Of these, however, many are unsatisfactory because in accommodating deviations from a standard size billet the position of the scarfing tips or burners in relation to the workpiece is changed. In some machines, for instance, the scarfing burners are supported on pivoted arms that swing in and out to accommodate billets of different sizes but the movement of the arms changes the angular relation of the scarfing oxygen jets with respect to the work surfaces. This is to be avoided if possible since it detrimentally affects the efficiency of the scarfing operation. In other machines the burners are so supported, as by folding parallelogram frames, that when they are moved toward or away from the billet the angularity of the scarfing oxygen jets with respect to the work surfaces does not change but such movement of the burners has a component of movement longitudinally of the billet and unless all of the burners are moved through the same distance to bring them into scarfing relation with the billet they will not, in their final position against the billet surfaces, be disposed in the same transverse plane. Consequently, the scarfing front at one surface of the billet does not coincide with the scarfing front at a contiguous surface and an undesirable flash or rewlid is often formed at the meeting edge of these two scarfed surfaces.

It is possible to overcome the above objections by mounting the members which carry the burners on slides each of which is movable rectilinearly toward and away from the billet, but the use of

slides is objectionable because the relatively slideable surfaces are extremely vulnerable to wear and also to the flying slag which can soon interfere with their proper functioning.

It is therefore an object of this invention to provide an improved scarfing machine that may be used for scarfing all four surfaces of rectangular billets and similar metal bodies simultaneously and whose scarfing burners can be moved rapidly into scarfing relation with the billet surfaces without changing the angularity of the scarfing jets with respect to the work surfaces or moving the burners out of the same general transverse plane and without resorting to the use of sliding parts to accomplish these results.

According to the invention the scarfing machine comprises a main support which extends on opposite sides of the mill roll table along which the billets are conveyed or which is movable to a position in which it has that relation with the mill roll table. Two burner carriers are mounted on the main support and lie at opposite sides of the billet when the machine is in scarfing relation with the billet. On each burner carrier there is mounted a scarfing burner, or two scarfing burners arranged in right angular relation so that one burner of the pair can scarf a side surface of the billet and the other one can scarf the top or bottom contiguous surface of the billet. There are two linkage structures each of which movably supports and guides one of the burner carriers on the main support. Each of these linkage structures comprises swinging arms which are pivoted to the main support at one side of the machine and which are pivotally interconnected by at least one link that forms with them and with the portion of the main support to which the arms are pivoted a folding parallelogram frame, herein called the primary folding parallelogram, and each of the linkage structures further comprises additional swinging arms which are pivotally connected to the primary folding parallelogram frame and to the burner carrier so as to form a second folding parallelogram frame which swings on the first one and which is herein called the secondary folding parallelogram frame. All of the pivot axes of the folding parallelogram frames are parallel to the longitudinal axis of the billet, and because of this fact, and because of the fact that each burner carrier forms a part of the secondary folding parallelogram frame that swings on the primary folding parallelogram frame each burner can be moved parallel to itself and in any direction in a vertical plane and without any accompanying component of

movement longitudinally of the billet. Consequently, the burners carried by the burner carriers can be moved in and out or up and down without changing the angularity of the scarfing jets with respect to the surfaces of the billet and without moving them out of the same general transverse plane.

Two forms of a scarfing machine embodying the invention are illustrated in the accompanying drawings, in which:

Figure 1 is a front elevation of one form of the machine;

Fig. 2 is a vertical section taken along the line 2—2 of Fig. 1;

Fig. 3 is a front elevation, partly in section, of one of the burner carriers and the parts carried by it;

Fig. 4 is a vertical section taken along the line 4—4 of Fig. 2;

Figs. 5 and 6 are schematic illustrations of the linkage structure that supports and guides one of the burner carriers, the two figures showing the position of the parts when the burner carrier is moved to different positions.

Fig. 7 is a front elevation of a modified form of the scarfing machine; and

Figs. 8 and 9 are schematic illustrations of the linkage structure that supports one of the burner carriers of the machine shown in Fig. 7, the two figures showing the position of the parts when the burner carrier is moved to different positions.

Referring first to Figs. 1-4, the scarfing machine therein illustrated has a main support or frame which comprises a wheeled carriage 10 (Fig. 1) movable along a track 11. The track extends transversely of the mill roll table so that the carriage can be moved to and from a position under it. One of the rolls of the mill roll table is represented at 12. It is journaled in stanchions 13 supported on the floor 14. A billet supported on the rolls of the mill roll table is represented at B. The track 11 is preferably located in a pit which extends transversely of the mill roll table so that the carriage 10 will be below the level of the floor 14. When the machine is in scarfing relation with the billet B on the mill roll table, carriage 10 extends on opposite sides of the billet, and by the linkage structures hereinafter described, supports the scarfing burners at the billet level.

The left side of the carriage 10 in Fig. 1 carries brackets 15 and 16 in which shafts 17 and 18 are mounted, respectively. An upright arm 19 swings about the axis of the shaft 17. As shown in Figs. 2 and 4, this arm may be an I-beam member which is formed integrally at its lower end with a sleeve 20 that surrounds and turns on the shaft 17. Two upright arms 21 (Figs. 1, 2 and 4) which constitute in effect a single arm, swing about the axis of the shaft 18. The upper end of the plate-like swinging arm 19 is formed integrally with a sleeve 22 (Figs. 2 and 4) through which a shaft 23 passes. A shaft 24 passes through the upper ends of the swinging arms 21, and the two shafts 23 and 24 are pivotally interconnected by a pair of links 25. The arms 21 may have collars 21' (Fig. 2) at their lower ends which surround the shaft 18 and may have collars 21'' at their upper ends which surround the shaft 24. Sleeves 21a position the collars on the shaft 18 and sleeves 21b position the collars on the shaft 24. As best seen from Figs. 1 and 4, the upright swinging arms 19 and 21 form with the portion of the

carriage to which they are pivoted and with the connecting links 25 a folding parallelogram frame. This is the primary folding parallelogram frame previously referred to. The shaft 18 is located at a higher level than the shaft 17 and the shaft 24 is located at a correspondingly higher level than the shaft 23, as shown in Fig. 1, so that the connecting links 25 are inclined at an angle of about 45°. This makes it possible to provide a second folding parallelogram frame based on the links 25 and which projects in a generally horizontal direction so that it can support one of the burner carriers at its free end. This folding parallelogram frame 15 is the secondary folding parallelogram frame previously referred to and includes a pair of swinging arms 26 (Figs. 1, 2 and 4) constituting in effect a single arm, which are pivotally connected at their outer ends to the shaft 23 and at their inner ends to a shaft 27 mounted in brackets 28 connected to the burner carrier 29. The secondary folding parallelogram frame also includes an arm 30 which is pivotally connected at its outer end to the shaft 24 and at its inner end to a shaft 31 mounted in the burner carrier 29. As best shown in Fig. 2, the burner carrier 29 is a frame made up of two transversely extending parallel channel members 32 and 33, a top horizontal plate 34 supported by them, and a vertical plate 35 (Figs. 1 and 4) connecting their inner ends. The above-mentioned brackets 28 in which the shaft 27 is mounted depend from the lower flanges of the two channel members 32 and 33, and the above-mentioned shaft 31 to which the inner end of the swinging arm 30 is pivoted is journaled in bearings 31' secured to the vertical webs of the two channel members as best shown in Fig. 2. A vertically disposed burner 36 for scarfing the left side surface of the billet as viewed in Fig. 1 is attached to the vertical plate 35 of the burner carrier as shown in this figure, and a horizontally disposed burner 37 for scarfing the top surface of the billet is supported on the horizontal plate 34 of the burner carrier. The burner 37 is slidably mounted on the plate 34 and is capable of limited horizontal adjustment thereon transversely of the machine for the purpose hereinafter described. The adjusting means for the burner 37 is best shown in Fig. 3. The burner is secured to a cylindrical bar 38 which is guided in blocks 39 in which the bar can slide longitudinally. The bar has a tapped drilling 40 in its distal end which receives a threaded spindle 41. This spindle is rotatably mounted in a bearing block 42 and carries a hand wheel 43 by which it can be rotated. When the threaded spindle 41 is rotated by means of the hand wheel the bar 38 is caused to move lengthwise and adjust the position of the scarfing burner 37. Referring again to Figs. 1 and 4, a link 44 similar to the upright swinging arm 19 supports the inner free end of the secondary folding parallelogram frame and helps impart up and down movement to it as hereinafter described. This link has a sleeve 45 at its upper end (Fig. 4) which surrounds and can pivot on the shaft 27. The lower end of the link has a similar sleeve 46 which surrounds and can pivot on a shaft 47 mounted in a lower link made up of two channel members 48 and 49 (Fig. 2). Only one of these channel members appears in Fig. 1 and the companion one appears in Fig. 4. At their outer ends they are fulcrumed on the shaft 17. One of these 70 two channel members has an outward extension

50 as shown in Fig. 1 which is pivotally connected at 51 to a piston rod 52 of a fluid cylinder 53. The fluid cylinder 53 is located in an enclosure 54 in which it is pivotally suspended at 55 by means of a bracket 56. The piston rod 52 is connected to a piston (not shown) which operates in the cylinder 53, and when motive fluid is admitted to and discharged from the cylinder by well-known means, not illustrated in the drawing, the piston may be moved in the cylinder to swing the link 48-49 about the axis of the shaft 17. Since the inner end of the link 48-49 is connected by means of the link 44 to the shaft 21 and hence to the free end of the secondary folding parallelogram frame, this will pivot the secondary parallelogram frame on the shafts 23 and 24 to thereby move the burner carrier 29 up or down, its successive positions always being in parallel relation. This movement of the scarfing burner carrier is schematically illustrated in Fig. 6 in which the full-lines represent the position of the parts in a relatively low position of the burner carrier and the dotted-lines represent their position in a more elevated position of the burner carrier. It will be noted that during the up and down movement of the scarfing burner carrier depicted in Fig. 6 the upright swinging arms 19 and 21 of the primary folding parallelogram frame do not move provided the fluid cylinder which actuates them as hereinafter described is allowed to remain idle at this time.

To effect in and out movement of the burner carrier in a generally horizontal direction, the sleeve 20 at the lower end of the upright swinging arm 19 has a pair of outwardly extending arms 57 formed integrally with it (Figs. 1, 2 and 4), and these arms are pivotally connected to the piston rod of a second fluid cylinder which lies directly behind the fluid cylinder 53 in Fig. 1 and therefore does not show in this figure. However, the second fluid cylinder is represented at 53a in Fig. 5 which is a schematic view similar to Fig. 6 illustrating the position of the parts when the burner carrier is moved in or out. The piston rod 52a of the fluid cylinder 53a is pivotally connected at 51a to the above-described arms 57 which form an integral part of the sleeve 20 at the lower end of the upright swinging arm 19. When motive fluid is admitted to and discharged from the cylinder 53a by well-known means not illustrated in the drawing, the arms 57 are actuated to swing the arm 19 of the primary folding parallelogram frame about the axis of the shaft 17. This pivots the entire primary parallelogram frame on the shafts 17 and 18 and imparts in or out movement to the scarfing burner carrier 29 through the secondary parallelogram frame. In Fig. 5 the full-lines represent the position of the parts when the burner carrier is in one position and the dotted-lines represent the position of the parts when the burner carrier is moved to a more outward position with respect to the billet by operation of the fluid cylinder 53a. It will be noted that if the fluid cylinder 53 is not operated at the same time as the fluid cylinder 53a, the secondary folding parallelogram frame will not pivot to any great extent on the shafts 23 and 24 during movement of the primary folding parallelogram frame. However, the link 44 will swing about the axis of the shaft 47 and will support and guide the inner end of the secondary parallelogram frame. The successive positions of the burner carrier during its movement will always be in parallel relation. Of course, both fluid cylinders 53 and 53a may be operated at the same

time if so desired to simultaneously impart both vertical and horizontal components of movement to the burner carrier. The burner carrier, and hence the scarfing burners carried by it, will always move in the same general vertical plane and the burners will always move parallel to themselves, i. e., their successive positions will be in parallel relation regardless of the direction of their movement.

A vertically disposed burner 58 and a horizontally disposed burner 59 for scarfing the other side surface of the billet and its bottom surface are supported at the right side of the machine (Fig. 1) by a burner carrier and a double folding parallelogram linkage similar to that above described except for the necessary reversal of parts. The same reference numerals have been used in the drawings to designate corresponding parts at the opposite sides of the machine. It should be noted, however, that, whereas the vertically disposed burner 36 at the left side of the machine is mounted directly on the vertical plate 35 of its burner carrier, the vertically disposed burner 58 at the right side of the machine is attached to a special bracket 60 supported on the top plate 34 of the burner carrier. The horizontally disposed burner 59 for scarfing the lower surface of the billet is slidably mounted on the burner carrier at the right side of the machine and adjusted thereon transversely of the machine in the same manner that the other horizontally disposed burner 37 is slidably mounted and adjusted on its carrier at the left side of the machine.

The two folding parallelogram frames at the right side of the machine are actuated by fluid cylinders in the same manner as those at the left side to impart in and out and also up and down components of movement to the pair of burners 58 and 59.

The oxygen discharge face of each burner is shown at f. In the position to which the upper and lower horizontally disposed burners 37 and 59 are adjusted in Fig. 1 the oxygen-discharge face of each of these burners extends about one-half of its length inwardly beyond the oxygen-discharge face of the companion vertically disposed burner that is mounted on the same burner carrier with it. This adjustment of the burners is suitable for a relatively narrow rectangular billet such as shown in Fig. 1. For successively wider billets the upper and lower horizontally disposed burners are adjusted so that a correspondingly greater portion of the oxygen-discharge face of each of them will project inwardly beyond its companion vertically disclosed burner. In Fig. 3 the broken-line position of the upper and lower horizontally disposed burners 37 and 59 represent the positions to which they may be adjusted for scarfing a billet B' having the maximum width which the machine is designed to scarf. The vertically disposed burners 36 and 58 will accommodate billets of any height up to the length of the oxygen-discharge faces of these burners. Since all of the burners of the particular machine illustrated in the drawings have oxygen-discharge faces f of the same length the largest billet which the machine illustrated is designed to scarf is the billet B' of square cross-section shown in Fig. 3.

It will now be seen that the machine will scarf billets or similar workpieces ranging in size from the minimum size to the maximum size which the machine will accommodate, and that for any billet within this range the scarfing burners can

be brought into contact with the surfaces of the billet by actuating the two folding parallelogram frames at opposite sides of the machine in the manner previously described. The burners are originally positioned in the same general vertical plane when the machine is assembled and they will not move out of this plane during their movement into scarfing position. The burners will always move parallel to themselves and the angularity of the scarfing jet passages will not change during movement of the burners into contact with the billet surfaces.

A flash or reweld could occur at the meeting edge of the two contiguous surfaces of the billet scarfed by the relatively movable burners 36 and 59 if the scarfing fronts of these two burners did not lie in substantially the same vertical plane when these burners are moved into contact with the billet surfaces, and the same is true with respect to the meeting edge of the two contiguous surfaces scarfed by the relatively movable burners 37 and 58. But since the linkage structures herein described move the burners 36 and 59 into contact with the billet surfaces they are intended to scarf without imparting any component of movement to either of them lengthwise of the billet, the scarfing fronts of these two burners will always lie in the same general vertical plane regardless of the size of the billet, and the same is true with respect to the burners 37 and 58.

A modified form of scarfing machine in which the burners are supported by linkage structures differing somewhat from those above described but operating on the same principle is shown in Fig. 7. In this form of the machine the linkage structure for each of the two burner carriers hangs downward from the superstructure of the machine as opposed to the machine previously described in which the linkage structure for each of the burner carriers extends upwardly from the base of the machine. The machine shown in Fig. 7 comprises a wheeled carriage 10' movable along a track 11'. As in the case of the first form of the machine, the track extends transversely of the mill roll table so that the carriage can be moved to and from a position under it, and the track is located in a pit so that the carriage will be below the floor level. One of the rolls of the mill roll table is represented at 12'.

An arch-like frame 61 is mounted on the carriage 10' which straddles the mill roll table and supports the linkage mechanism for the burner carriers. The burners are shown at 62, 63, 64 and 65. Burner 62 for scarfing the top surface of the billet and the companion burner 63 for scarfing the right side surface of the billet as viewed in Fig. 1 are mounted on a frame 66 which constitutes a burner carrier for these two burners. The burner 64 for scarfing the bottom surface of the billet and the burner 65 for scarfing the left side surface of the billet as viewed in Fig. 7 are mounted on a frame 67 which constitutes a burner carrier for these two burners.

The burner carrier 67 hangs on arms 68 and 69 which depend from shafts 70 and 71 respectively. The shafts 70 and 71 are connected by a link 72 and are held in suitable bearings carried by the distal ends of two arms 73 and 74. The arm 73 pivots about a fixed shaft 75 supported near the upper lefthand corner of the arch-like frame 61, and the arm 74 pivots about a fixed shaft 76 mounted in brackets 77 (only one of which appears in Fig. 7) supported on the top of the arch-like frame. The two arms 73 and 74, the link 72, and the portion of the arch-like frame 75

to which the arms 73 and 74 are pivoted, constitute a primary folding parallelogram frame corresponding to the primary folding parallelogram frame in the first form of machine previously described. The arms 68 and 69, the link 72, and the portion of the burner carrier to which the arms 68 and 69 are pivoted, constitute a secondary folding parallelogram frame corresponding to the secondary folding parallelogram frame in the first form of the machine. The primary folding parallelogram frame pivots about the shafts 75 and 76 and the secondary folding parallelogram frame pivots about the shafts 70 and 71. It will thus be seen that the two folding parallelogram frames can be operated to move the burner carrier in and out or up and down with no component of movement in a direction lengthwise of the billet and the movement of the burner carrier will always be parallel to itself.

The arm 74 is extended beyond its pivot shaft 76, as shown, and is pivotally connected at 78 to a fluid cylinder 79, the piston rod of which is pivotally connected at 80 to a bracket 81 attached to the side of the arch-like frame 61. Motive fluid admitted to and discharged from the cylinder 79 by well-known means, not shown in the drawing, actuates the linkage to move the burner carrier 67 up or down. A second fluid cylinder 82 pivotally connected to the bracket 81, and whose piston rod 83 is pivotally connected to the burner carrier 67, may be operated in a similar way to swing the depending arms 68 and 69 about the axes of the shafts 70 and 71 and impart in and out movement to the burner carrier.

The adjustments of the burner carrier 67 by operation of the two fluid cylinders 79 and 82 is schematically illustrated in Figs. 8 and 9. In Fig. 8 the full-lines represent the position of the parts in an inward position of the burner carrier 67 and the dotted-lines represent the position of the parts when the fluid cylinder 82 is operated to move the burner carrier outwardly while the fluid cylinder 79 is allowed to remain idle. In Fig. 9 the full-lines represent the position of the parts for a relatively low position of the burner carrier 67 and the dotted-lines represent the position of the parts when the fluid cylinder 79 is operated to move the burner carrier upwardly while the fluid cylinder 82 is allowed to remain idle. Both of the fluid cylinders may be operated simultaneously, if desired, so that both sets of movements shown in Figs. 8 and 9 may occur at the same time.

The mechanism for supporting and moving the burner carrier 67 is duplicated at the opposite side of the machine with the necessary reversal of some of the parts, for supporting and moving the burner carrier 66. Corresponding parts at opposite sides of the machine are designated by the same reference numerals in the drawing.

As in the case of the first form of the machine, certain of the scarfing burners are adjustably mounted on the burner carriers to accommodate billets of different width. In this case the two vertically disposed burners 63 and 65 are adjustable horizontally toward and away from the billet as shown at 84 to vary the amount which the upper burner 62 projects to the left beyond the burner 63 and to vary the amount which the lower burner 64 projects to the right beyond the burner 65.

In both forms of the machine, operation of the fluid cylinders will cause the linkage structures that support and guide the two burner carriers to move the scarfing burners toward the billet

and each burner will automatically assume its proper position in contact with the corresponding surface of the billet. The burners are moved to scarfing position against the surfaces of the billet without varying the angularity of the scarfing jets and without imparting to any of the burners a component of movement axially of the billet and which would tend to cause the scarfing front of the burners carried by the burner carrier at one side of the machine to lie in a different vertical plane from the scarfing front of the burners carried by the burner carrier at the opposite side of the machine, and these things are accomplished without resorting to the use of any sliding parts in the supporting and guiding mechanism for the burner carriers.

I claim:

1. A scarfing machine for scarfing the surfaces of billets and similar metal bodies, comprising a main support, means for obtaining relative movement between a billet and said main support in a path extending in a direction lengthwise of the billet, two burner carriers having parts positioned at opposite sides of said path, a scarfing burner mounted on each of said parts of said carriers, each burner comprising a series of orifices extending in at least two directions to direct a scarfing flame onto at least two adjacent sides of a billet, means for maintaining said burners substantially in alignment in a direction transversely of said path and for moving said burners toward and from said path in a direction parallel to themselves, said means including two linkage structures each movably supporting one of said burner carriers on the main support, each of said linkage structures comprising swinging arms piv-

oted to the main support at one side of the billet, at least one link pivotally interconnecting said arms and forming with them and with the portion of the main support to which they are pivotally connected a folding parallelogram frame, and additional swinging arms pivotally connected to a portion of said folding parallelogram frame and to the corresponding burner carrier so as to form a second folding parallelogram frame which swings on the first one, all of the pivot axes of the folding parallelogram frames being parallel to the longitudinal axis of the billet.

2. A scarfing machine in accordance with claim 1 having power means operatively connected to a part of the first folding parallelogram frame of each linkage structure for swinging its arms about their pivotal connections to the main support and for holding such arms in the position to which they are swung, and power means operatively connected to a part of the second folding parallelogram frame of each linkage structure for swinging its arms about their pivotal connections to the first folding parallelogram frame and for holding such arms in the position to which they are swung.

JOSEPH M. TYRNER.
